FIG. 3 is an enlarged right side view thereof;

FIG. 4 is an enlarged left side view thereof;

FIG. 5 is a top and right side perspective view thereof; and,
FIG. 6 is a top and left side perspective view thereof.

The rear view is omitted because it is represented symmetrically to the front view.

The bottom plan view is omitted because it is represented identically with the top plan view.

The connecting hose for dental handpiece is shown in FIGS. 1, 2, 5, and 6 broken in the middle for ease of illustration.

Portions of the connecting hose for dental handpiece shown in broken lines in FIGS. 3 and 4 form no part of the claimed design.
